(57) **CLAIM**

The ornamental design for a keyboard layout for a protective folio, as shown and described.

DESCRIPTION

FIG. 1 is a perspective view of the keyboard layout for a protective folio showing our new design;

FIG. 2 is a top plan view thereof;

FIG. 3 is another perspective view thereof, shown without the unclaimed protective folio; and,

FIG. 4 is a top plan view thereof.

The broken lines shown represent unclaimed subject matter and form no part of the claimed design.

1 Claim, 4 Drawing Sheets
